UNITED STATES PATENT OFFICE.

HERMAN PENGELLY WILLIAMS, OF ST. LOUIS, MISSOURI.

POURING DEVICE.

Application filed February 19, 1924. Serial No. 693,779.

The present invention relates to pouring devices, such as ladles for pouring molten metal, and more particularly to the means for controlling the discharge of the metal from the ladle.

Among the objects of the invention are to provide a novel discharge nozzle having an exterior or external stopper-engaging seat in lieu of an interior or internal seat, with the advantage of subjecting the seat to less abrasion whereby the seat may retain its original shape longer, aiding in the self-aligning and the self centering of the stopper when being moved to closing position, reducing the tendency to leakage and the wastage of the molten material with its attendant hazard or danger to the workmen, and aiding in effecting a tortuous flow of the molten material; to provide such nozzle with a surface so shaped that a small area of contact or even a mere line of contact between it and the stopper will suffice to form an effective seal or closing of the nozzle against discharge and leakage of the molten material; to so locate the nozzle in the bottom of the ladle so that its seating or upper end will be in raised position above the bottom of the ladle, the latter being preferably formed with a recess or well about the nozzle, with the advantage of preventing the contents of the ladle from coming directly into contact with the seat and facilitating the seating and holding closed of the stopper upon the nozzle; to so form the seat that it will aid in self-centering the stopper when being moved to closing position; to provide a stopper which will make contact with the outside of the nozzle instead of interiorly; to provide the stopper with an interior or internal seating and sealing portion, preferably in the form of a replaceable insert of suitable substance, such as graphite, which may become slightly plastic at the temperature of the molten material with the advantage of such substance conforming itself to the slight irregularities of the surface of the nozzle seat to form an effective seal and closing of the nozzle against discharge or leakage of the molten material when the stopper is in closing position; to provide the stopper seating portion with preferably a tapering or inclined surface to aid in effecting a self-centering and aligning of the stopper when being moved to closing position and also to cooperate in effecting the small area or line contact with the

nozzle seat; to provide the stopper with protecting means, such as a depending portion surrounding the upper end of the nozzle so as to prevent contact with the seating portions of both the nozzle and the stopper from external objects, the depending portion dipping into the well in aid of this object; to provide for a tortuous passage of the molten material to the nozzle by the depending portion of the stopper extending below the upper or inlet end of the nozzle, the extent of the dip of said portion into the well aiding this object; and to provide such other objects, advantages and capabilities as will hereinafter appear and as are inherently possessed by the invention.

In the drawing showing an illustrative embodiment of the invention,—Fig. 1 is a view, in vertical section, of a ladle equipped with a device constructed in accordance with the invention, and Fig. 2 is an enlarged sectional view of the device and a fragment of the ladle bottom.

Referring more in detail to the drawing, the invention is shown as comprised in a ladle having an exterior metal sheathing 1 and an interior lining of refractory material 2. The ladle is provided with a bottom having a suitable aperture therein for the reception of a nozzle member 3 provided with a discharge passage or orifice 4 formed with a tapered inlet portion 5 as clearly shown in Fig. 2 of the drawing. The upper end of the nozzle 3 is formed with a tapered surface 6 providing an external or exterior seat. This surface 6 may be curved so that its contact with a stopper member 7 may be of small area or even a mere line contact. The bottom of the ladle may be provided with a depression or recess 8 surrounding the upper end of the nozzle 3 so as to form a sort of well about the upper or seating end of the nozzle, as clearly shown in Fig. 2 of the drawing. The nozzle may be formed of refractory material suitable for the use to which it may be put.

Above the nozzle and vertically movable toward and from the same is a stopper comprising a sleeve member 9 having an annular depending portion 10 capable of surrounding the upper end of the nozzle 3 when the stopper is in lowered or closed position. The lower end of the member 9 is internally recessed to replaceably receive a seating or sealing member 7 which may be of any suitable refractory material, or ma-

terial such as graphite and the like, or if desired, both the nozzle 3 and the member 7 may be of the same material. The member 7 is entirely enclosed within surrounding portion 10 and is protected thereby from contact from any external objects. The lower portion of member 7 is internally inclined or tapered to conform approximately to the shape of the seat 6 of the nozzle 3.

10 Preferably, the inclined surface 11 of the member 7 is slightly different than the surface 6 so that there will be a small area of contact or a mere line of contact between the two surfaces 6 and 11. It is also preferred that the material 7 be such that it may become slightly plastic at the temperature of the molten material in the ladle so that when the stopper member is lowered into seating position the member 7 may conform itself to whatever irregularities may be present in the surface 6 of the nozzle. In this way leakage and wastage of the molten material will be prevented and hence the danger and hazard to the workmen entirely avoided.

15 It will be noted that the molten material must take a tortuous path about the lower end of the surrounding portion 11 and then upwardly between the surfaces 6 and 7 before it may pass downwardly into the orifice 4. In this way the tendency of contact of the molten material is substantially along the surfaces 6 and 11 instead of directly thereupon or at right angles thereto. This aids in self-cleaning of the material that may tend to adhere to the surfaces 6 and 11 and when the stopper is in lowered position there is no direct contact by the molten material with the seating surfaces. The surrounding member 10 also aids in protecting the seat 6 from contact from external objects, the well 8 permitting a certain amount of dip or extension of the member 10 therein both for the protection above mentioned and also for effecting the tortuous passage of the material during the discharge action.

20 The member 9 is preferably made of refractory material and centrally apertured to receive an operating rod 12 having, at its lower end, a head 13 fitting into a suitable recess in the member 7 or, if desired, entirely imbedded therein. The rod 12 extends upwardly to the upper part of the ladle and is connected, to suitable means, (not shown) for raising and lowering the stopper when it is desired to control the discharge of the molten material from the ladle. Inasmuch as the mechanism for raising and lowering the stopper is not involved in the invention herein disclosed, it is not necessary to describe such mechanism. The rod 12 is preferably surrounded, throughout the length thereof, with refractory material such as sleeves 14 as clearly shown in the drawing.

25 The particular construction herein dis-

closed has the advantage of not permitting the freezing of the molten material to the seats of the nozzle and stopper, the relation of the path of flow of the material and the surface of the seat being such that the surfaces of the seat will be self-cleaning.

70 While I have herein described and upon the drawing shown a preferred embodiment of the invention, it is to be understood that the invention is not limited to the particular details, arrangement of parts, and construction shown and described, but that it also comprehends other details, arrangements of parts, and constructions, without departing 75 from the spirit thereof.

80 Having thus described my invention, I claim:

1. A nozzle for pouring ladles, comprising an exteriorly tapered stopper-engaging seat and a discharge passage.
2. A nozzle for pouring ladles, comprising an exteriorly tapered stopper-engaging seat having a small area of contact with a stopper, and a discharge passage.
3. In a pouring ladle, a nozzle in the bottom of said ladle and having an exteriorly tapered stopper-engaging seat at a distance above said bottom.
4. In a pouring ladle comprising a bottom having a recess therein, a nozzle in said bottom and having a stopper-engaging seat located above the bottom of said recess.
5. In a pouring ladle comprising a bottom, a nozzle extending through said bottom and having a tapered exterior stopper-engaging seat at the upper end thereof, and a stopper having an interior seat for engaging said nozzle seat.
6. In a pouring ladle comprising a bottom, a nozzle in said bottom for discharging contents of the ladle therethrough, a stopper movably cooperative with said nozzle to control flow of the contents through the nozzle, said nozzle and stopper having respectively exterior and interior engaging seat portions.
7. In a pouring ladle comprising a bottom, a discharge nozzle in said bottom and having a valve seat portion, a stopper member having a valve seat portion cooperating with the seat portion of the nozzle to shut off flow of molten material from the nozzle when the stopper is in closed position, said stopper having means for causing a tortuous passage of the material to the nozzle when the stopper is in operative position.
8. In a pouring ladle comprising a bottom, a discharge nozzle in said bottom and having a valve seat at its upper end, a stopper having a valve seat at its lower end and movable to close and open the passage of molten material from and to said nozzle, said stopper having a depending portion surrounding said seats for causing the material to take a tortuous path when the stopper is in open position.

9. In a pouring ladle comprising a bottom, a discharge nozzle in said bottom and having a stopper-seating portion, a stopper therefor, said stopper having a sealing member for said seating portion and composed of a substance which is slightly plastic at the temperature of the molten metal in the ladle whereby the sealing member may conform itself to the irregularities of the surface of the seating portion to form a seal against leakage of the material when the stopper is in closed position. 30
10. A stopper for pouring ladle nozzles, comprising an interiorly tapered seat portion, and means for protecting said seat portion from contact from exterior objects. 35
11. A stopper for pouring ladle nozzles, comprising an interior seat portion having an interiorly tapered surface for seating 20 upon the nozzle and for self-centering the stopper to the nozzle when being moved into closing position.
12. A stopper for pouring ladle nozzles, comprising a depending portion capable of 25 surrounding the end of the nozzle, a seating member in the depending portion and having a seating surface for engagement with the nozzle when the stopper is in closing position.
13. A stopper for pouring ladle nozzles, comprising an outer member of refractory material, and an interiorly tapered inner seat-engaging member of soft material. 40
14. A stopper for pouring ladle nozzles comprising an outer member of refractory material, and an inner seat-engaging member of graphite.
15. A stopper for pouring ladle nozzles comprising a body member having a recess for holding a seat-engaging member, and an interiorly tapered seat-engaging member replaceably held in said recess. 45
16. A stopper for pouring ladle nozzles, comprising an outer member of relatively hard material and having a recess, an inner member of relatively soft material replaceably held in said recess and having an interiorly tapered seat-engaging portion. 50

In witness whereof, I hereunto subscribe my name to this specification.

HERMAN PENGELLY WILLIAMS.
